UNITED STATES PATENT OFFICE.

JAMES TRIPPLETT, OF COLUMBIA, KENTUCKY, ASSIGNOR OF ONE-HALF TO A. D. PATTESON, OF COLUMBIA, KENTUCKY.

MANUSCRIPT-HOLDER.

1,080,502.

Specification of Letters Patent.

Patented Dec. 2, 1913.

Application filed April 20, 1912. Serial No. 692,105.

To all whom it may concern:

Be it known that I, JAMES TRIPPLETT, a citizen of the United States, residing at Columbia, in the county of Adair and State 5 of Kentucky, have invented new and useful Improvements in Manuscript-Holders, of which the following is a specification.

The general object of the invention is to obviate the turning by the reader, of the various leaves of a manuscript while the reading therefrom is in progress; and to this end the invention consists in certain improved constructions, arrangements and combinations of devices, which will be fully described hereinafter, and then pointed out in the claim.

Other objects will appear and be better understood from that embodiment of my invention of which the following is a specification, reference being had to the accompanying drawings, forming a part hereof, in which;

Figure 1 is a plan view of the device. Fig. 2 is a vertical longitudinal section. 25 Fig. 3 is a side elevation partly in section.

In the drawings *a* indicates a frame of any suitable material, such as metal, and of any suitable shape, such as rectangular. The base *b* of this frame is of such size as 30 to prevent the frame from toppling over while in use and the bearing surface of the base is flat so that it will rest evenly on the holder of an ordinary lecture stand or pulpit, and smooth so as not to scratch or abrade 35 the stand, and the length of the frame is such as to admit of the extension horizontally of a section of paper approximating the length of the ordinary sheet of manuscript between its ends.

40 The manuscript *c* consists of a continuous sheet of paper of less width than the frame *a*. The matter to be read is printed or written on one face of the sheet and it will be understood, of course, that the length 45 of the sheet will be determined by the amount of reading matter which it is to carry.

When the manuscript is prepared it is coiled upon a let-off in the form of a drum 50 or roll *d*. This drum or roll *d* carries a clip 8 beneath which one end of the manuscript *c* is tucked. A shaft 9 having bearings in the opposite sides 10-10 of the frame, extends loosely through the drum *d* and has 55 fastened to it a wheel 11 which carries a

spring-pressed dog or pawl 12 which engages with the teeth of a ratchet 13 secured to one end of the drum *d* and co-operating with the pawl to prevent independent turning of the drum in one direction on the 60 shaft 9.

The manuscript is directed from the drum 7 over a table 14 which prevents the manuscript from being accidentally depressed and torn. When the reader has occasion to keep 65 note of a certain line on the exposed portion of the manuscript by placing his finger on the line, which, as is well-known, is frequently done when the reader looks at his audience and makes remarks supplementing 70 matter in the manuscript. The table extends substantially tangentially of the drum 7 and is suitably supported by a post 15, rising from the base *b* of the frame. In directing the manuscript over the table the 75 said manuscript is inserted through guides 16-16 at the opposite ends of the table, and from the guide remote from the drum 7 the manuscript is directed onto a take-up in the form of a drum 17. The drum has a clip 18 80 under which the end of the manuscript is tucked and a shaft 19 to which the drum is secured, serves to support the drum and has its opposite end portions rotatably mounted in bearings in the sides 10-10 of 85 the frame *a*. The take-up or drum 17 is turned in the same direction as the drum 7 by means of a pinion 20 fast on the shaft 19 and a toothed wheel 21 on a shaft 22 which has bearings in one of the sides 10 of 90 the frame and a bracket 23 carried by the said side. A dog or pawl 24 is held by gravity and a spring 25 in contact with a ratchet wheel 26 on the shaft 22 and a pivot 27 carried by the section 28 of an operating 95 lever, serves as a support for the dog 24. A pivot 29 in a side of the frame *a*, supports one end of the section 28 of the operating lever and a spring 30 presses upwardly 100 on the opposite end of the operating lever and serves to hold the latter so that the dog carried thereby will normally engage with the top or uppermost tooth of the ratchet 26. The section 31 of the operating 105 lever which is pivoted to the free end of the section 28, is projected upwardly and at its upper end carries a button 32 which, when pressure is applied by the finger of the operator, causes the sections of the operating lever to move downwardly and thereby move 110

the dog for a distance sufficient to turn the ratchet 26 a quarter of a revolution or approximately so.

The gearing connection between the shafts 5 19 and 22 is such as to turn the drum 17 for a full revolution or approximately so and the drum measures in circumference approximately the same as the table 14. Thus, it will be seen that when the reading of the 10 matter of that portion of the manuscript overlying the table is about finished, an equal amount of new or unread matter may be brought into view by pressing downwardly as far as possible on the button 32. 15 This operation, namely that of pressing the button 32, is performed upon the completion of the reading of each exposed section of the manuscript. Upon the completion of the reading of the last section of the manuscript, the dog 24 is lifted from engagement 20 with the ratchet 26 and the shaft 9 turned by the crank handle 33 so as to unwind the manuscript from the take-up. This done, the manuscript is unrolled by the operator, 25 from the let-off or drum 7.

The crank handle 34 on the shaft 19 is for the purpose of turning the take-up when the manuscript is first connected thereto and is turned until the first section of reading 30 matter is over the table 14.

When the operating lever is pressed downwardly as far as it will go it may be held in this position by moving the section 31 toward the adjacent end of the frame and 35 entering the shaft 9 in the detent or notch

35 formed in the section 31. This is done when the device is not in use and the friction caused by the pressure of the wall of the detent on the shaft 9, serves to lock the parts against turning movement. 40

A bow spring 36 is arranged so that its opposite ends will bear on the let-off and take-up and serves to prevent return movement or too free rotation of these elements when the device is in use. 45

What is claimed as new is:

A manuscript holder including a supporting frame, a rotatable feed device mounted in one end of the frame and upon which the manuscript is coiled, a rotatable take-up 50 device mounted in the opposite end of the frame to which one end of the manuscript is connected, a table arranged between and above said take up and feed device, a gear operatively connected with the take up device, a lever mounted in the frame, a push rod normally projecting above the table and connected to the lever, means intermediate the lever and gear to operate the gear a pre-determined distance upon each depression of 55 the push rod, said push rod being formed with a notch to frictionally coöperate with the shaft of the feed device to lock the same against rotation.

In testimony whereof I affix my signature 60 in presence of two witnesses.

JAMES TRIPPLETT.
